United States Patent Office

Des. 191,938
Patented Dec. 19, 1961

191,938

WATER CLOSET OR SIMILAR ARTICLE

Hazel P. Rodman, 1315 S. Union St., Alliance, Ohio

Filed June 28, 1961, Ser. No. 65,745

Term of patent 14 years

(Cl. D4—5)

FIG. 1

FIG. 2

FIG. 3

FIG. 4

FIG. 1 is a top plan view of a water closet embodying my new design.

FIG. 2 is a side elevation thereof.

FIG. 3 is a bottom plan view thereof.

FIG. 4 is a front elevation thereof.

The back of my design is plain and the side not shown is substantially the same as that shown in FIG. 2.

I claim:

The ornamental design for a water closet or similar article, substantially as shown and described.
